UNITED STATES PATENT OFFICE.

CASSIUS M. BARTHOLOMEW, OF COLUMBUS, OHIO.

RING-TWIRLING TOY.

SPECIFICATION forming part of Letters Patent No. 595,594, dated December 14, 1897.

Application filed February 27, 1897. Serial No. 625,264. (No model.)

To all whom it may concern:

Be it known that I, CASSIUS M. BARTHOLOMEW, a citizen of the United States, residing at Columbus, in the county of Franklin 5 and State of Ohio, have invented certain new and useful Improvements in Ring Twirling and Returning Toys; and I do hereby declare the following to be a full, clear, and exact description of the invention, such as will enable others skilled in the art to which it 10 pertains to make and use the same.

The object of my invention is to provide a toy of simple and inexpensive construction that shall afford amusement and instruction 15 as well as exercise for the eye and hand of the user.

My invention is embodied in a device consisting of a shaft having at one end a support adapted to hold and catch a ring and at 20 the other a spring and devices by the proper manipulation of which the ring may be both projected into and twirled in the air, as hereinafter fully set forth.

In the annexed drawings, Figure 1 is a side 25 elevation of the toy with its accompanying ring. Fig. 2 is a similar view of a part of the shaft, showing added devices for automatically twisting the shaft when it is drawn down to distend the spring to its projecting 30 position; and Fig. 3 is a top plan view.

Like characters of reference in the different views designate corresponding parts.

1 designates the shaft or stem of the toy. At the upper end of this are secured a number 35 of triangular-shaped wings 2, having edges inclined to and meeting in a point at the upper extremity of the shaft. Upon the lower end of the shaft is a coiled spring 3, that has its lower end fastened in the shaft 40 and its upper end fastened in a sleeve or collar 4, that is capable of being turned laterally and slid longitudinally upon the shaft.

5 designates a ring consisting, preferably, of a flat strip of paper or other light and moderately-stiff material having its ends joined to 45 form a cylinder. The ring is preferably made of such diameter as to rest upon the lower portions of the outer edges of the wings 2.

The toy, as shown in Fig. 1, is used as follows: The ring is placed upon the supporting-wings in substantially the position shown 50 in this figure. The sleeve or collar 4 is held

in the fingers of one hand and the shaft or rod pulled down and turned at the same time, so as to "wind up" the spring with the other 55 hand. If the end of the shaft be now suddenly released, the ring will be projected into the air with a rotary motion. If the toy be held at an angle to the vertical when the ring is projected and rotated, the ring will return 60 toward the operator after its outward flight has ceased, as the rotary motion of the ring will continue. The returning ring may thus be caught by the operator upon the winged end of the shaft or stick without moving from 65 his original position on the floor or ground.

In addition to the parts shown in Fig. 1 I may employ a string or cord 6, as shown in Fig. 2. This cord is fastened to the shaft at its upper part and passed with a turn or two, 70 as may be required, around the shaft and preferably through a small loop or staple 7, and finally through a small eye or loop 8 at the lower end of the shaft. The cord is secured in such manner that when the sleeve 75 or collar 4 is held fixedly in one hand and the shaft or rod pulled down therethrough by the end of the string in the other the string in its engagement with the collar and loop will twist or rotate the shaft or rod and place it 80 under the necessary tension of the spring for rotating the ring when it is projected.

I have herein chosen the best means known to me of embodying my invention in tangible form, but do not wish to be understood as 85 limiting myself thereto, as it is susceptible of some modification without departing from the scope of my invention. The collar, for instance, may be omitted and the upper part of the spring taken in the fingers. 90

What I claim, and desire to secure by Letters Patent, is—

1. A toy consisting of a shaft having wings adapted to support loosely an open cylindric ring on its edge, and a spring attached to said 95 shaft whereby the latter may be placed under lateral and longitudinal tension so that when released it shall project and twirl said ring, substantially as set forth.

2. A toy consisting of a shaft 1 having wings 100 2 adapted to support loosely an open cylindric ring on its edge, a loose collar 4 on said shaft, a spring attached to said collar and shaft whereby the latter may be placed under lat-

eral and longitudinal tension so that when released the ring shall be projected and twirled, substantially as set forth.

3. A toy consisting of a shaft 1 having wings 5 2 tapered toward the end of said shaft adapted to support loosely an open cylindric ring on its edge, and a spring attached to said shaft whereby the latter may be placed under lateral and longitudinal tension, so that when 10 released it shall project and twirl said ring, substantially as set forth.

4. A toy comprising a rod or shaft having wings meeting at a point at their upper ends adapted to support a loose ring, a collar on 15 said shaft or rod, a spring attached to the collar and to the shaft, and a ring adapted to be

supported upon, projected from and caught upon said wings.

5. In a body-projecting toy, a shaft, a movable sleeve or collar on said shaft, a spring 20 attached to said shaft and to said collar or sleeve, and a cord 6 attached to said shaft above the sleeve or collar and engaging said collar and the shaft at a point near the shaft below the collar for the purpose explained. 25

In testimony whereof I have hereto affixed my signature in the presence of two witnesses.

CASSIUS M. BARTHOLOMEW.
